UNITED STATES PATENT OFFICE.

CLARENCE A. BOODIE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed September 11, 1920. Serial No. 409,720.

To all whom it may concern:

Be it known that I, CLARENCE A. BOODIE, a citizen of the United States, and a resident of Pittsburgh, in the county of Allegheny and State of Pennsylvania, have invented a new and useful Improvement in Electric Furnaces, of which the following is a specification.

My invention relates to electric furnaces of the movable-electrode type and, particularly, to electric furnaces of relatively large capacity.

One object of my invention is to provide an electric furnace of the movable-electrode type that shall have a plurality of sets of electrodes so connected to a polyphase supply circuit as to prevent flow of current from one set of electrodes through the bath of material being treated to an adjacent set of electrodes.

In modern electric-furnace practice, the capacity of the furnace is limited by the amount of current which can be transmitted by the movable electrodes. The current-carrying capacities of the electrodes are limited by the so-called "skin effect" and eddy currents induced in adjacent parts which are composed of magnetic material. Moreover, the electrode contact troubles develop so rapidly with increase in the current as to limit the practical furnace capacity.

It has been proposed to operate a number of sets of electrodes in parallel-circuit relation but, in such case, the electrodes would not evenly divide the load on the furnace. In the above case, stabilizing reactances would be necessary and such reactances are objectionable.

In a furnace constructed in accordance with my invention, a plurality of sets of electrodes are associated with one bath of material contained within one hearth. The sets of electrodes are connected to one supply circuit in such manner as to prevent flow of current from one set of electrodes to an adjacent set of electrodes. Each electrode of each set is operated in any well-known manner in accordance with the current or the watts supplied to the furnace or in accordance with any other electrical characteristic of the furnace operation.

Although only three sets of electrodes have been illustrated in the drawing, it is to be understood that any desired number of

sets of electrodes may be provided in the furnace. In the furnace illustrated, three sets of electrodes are connected by transformer means to a three-phase supply circuit. Each set of electrodes comprises three electrodes, and the transformer means comprises three primary coils and nine secondary coils. The three primary coils are connected to the supply circuit, either in delta or star relation, as may be desired. Each set of electrodes has three secondary windings connected to them and such secondary windings are respectively associated with the three primary windings. The secondary windings associated with each set of electrodes may be connected in delta or star relation, as desired.

In the accompanying drawing, Fig. 1 is a diagrammatic view of an electric furnace constructed in accordance with my invention, and

Fig. 2 is a diagrammatic view showing a different arrangement of the electrodes.

Referring to the drawing, an electric furnace 1, comprising a hearth 2 and a bath of material 3, is operated by a three-phase supply circuit comprising conductors 4, 5 and 6. A plurality of sets of electrodes 7, 8 and 9 are connected to the supply conductors 4, 5 and 6 through a bank of transformers 10. The set of electrodes 7 comprises electrodes 11, 12 and 13, the set of electrodes 8 comprises electrodes 14, 15 and 16, and the set of electrodes 9 comprises electrodes 17, 18 and 19.

The bank of transformers 10 comprises three primary windings 20, 21 and 22 and nine secondary windings 23 to 31 inclusive. The secondary coils 23, 26 and 29 are associated with the set of electrodes 7; the secondary coils 24, 27 and 30 are associated with the set of electrodes 8, and the secondary coils 25, 28 and 31 are associated with the set of electrodes 9.

The bank of transformers 10 may be constructed in one unit or may be constructed in a plurality of units, as desired, and, moreover, as above set forth, either the primary coils or the different sets of secondary coils may be connected either in star or in delta-circuit relation. Although each electrode 105 may be raised and lowered in any well-known manner and in accordance with any characteristic of operation of the furnace,

- it is preferred to operate each electrode by the regulator system described in my co-pending application, Serial No. 306,725, filed January 25, 1919. The electrodes 11 to 19, inclusive, may be longitudinally arranged, as shown in Fig. 1 of the drawing, or the electrodes of each set may be triangularly arranged, as shown in Fig. 2 of the drawing.
- 10 Modifications in the furnace, and in the arrangement and location of parts may be made within the spirit and scope of my invention, and such modifications are intended to be covered by the appended claims.
- 15 I claim as my invention:—
1. In an electric furnace, the combination comprising a plurality of sets of electrodes, a three-phase supply circuit, and single transformer means for so connecting said sets of electrodes to the supply circuit as to prevent flow of current from one set of electrodes to an adjacent set of electrodes.
  2. In an electric furnace, the combination comprising a plurality of sets of electrodes, a polyphase supply circuit, and single transformer means for so connecting the sets of electrodes to the supply circuit as to prevent flow of current from one set of electrodes to an adjacent set of electrodes.
  3. In an electric furnace, the combination with a plurality of sets of electrodes, each of said sets comprising three electrodes, and a three-phase supply circuit, of single transformer means for connecting said sets of electrodes to the supply circuit, said means comprising three primary coils and each of said sets of electrodes having a secondary coil associated with each of said primary coils.
  4. In an electric furnace, the combination with a plurality of sets of electrodes, and a polyphase supply circuit, of single trans-

former means for connecting said sets of electrodes to the supply circuit, said means comprising a plurality of primary coils and each of said sets of electrodes having a secondary coil associated with each of said primary coils.

5. In an electric furnace, the combination with a plurality of sets of electrodes, a single bath of material associated with said electrodes, and a polyphase supply circuit for supplying energy to the sets of electrodes, of single transformer means for so connecting said sets of electrodes to the supply circuit as to prevent flow of current from one set of electrodes to an adjacent set of electrodes.

6. In an electric furnace, the combination with a single hearth containing a bath of material, a plurality of sets of electrodes associated with said bath, each of said sets comprising three electrodes, and a three-phase supply circuit, of transformer means for connecting said sets of electrodes to the supply circuit, said means comprising three primary coils and secondary coils equal in number to the number of said electrodes and so interconnected as to prevent flow of current from one set of electrodes to an adjacent set.

7. In an electric furnace, the combination comprising a plurality of sets of electrodes, a polyphase supply circuit, a transformer means for connecting said sets of electrodes to a supply circuit, said transformer means comprising a plurality of primary coils and a plurality of secondary coils respectively associated with said primary coils and with each set of electrodes.

In testimony whereof, I have hereunto subscribed my name this 8th day of September, 1920.

CLARENCE A. BODDIE.
